UNITED STATES PATENT OFFICE.

HOWARD F. LYMAN, OF MITCHELL, SOUTH DAKOTA, ASSIGNOR OF ONE-HALF TO
ALBERT T. LYMAN, OF MOUNT VERNON, SOUTH DAKOTA.

ATTACHMENT FOR CORN BINDERS.

Application filed September 8, 1926. Serial No. 134,203.

This invention relates to attachments for corn binders and more particularly to a device for preventing actuation of the corn binder before a proper bundle has been gathered in 5 the binding mechanism.

A further object of the invention is to provide a device of this character which supplements and increases the resistance of the trip elements which control actuation of the corn 10 binder until the proper bundle has been assembled.

A further and more specific object of the invention is to provide a swinging arm which may be readily attached to a normal part of 15 the corn binder and be positioned substantially immediately above the binding control trips, so that corn which is at an inclination, in entering between the boards of the binder, will first engage with this arm and be held 20 thereby to prevent its engagement with the trip arm until the proper amount of corn has been gathered.

These and other objects I attain by the construction shown in the accompanying drawings, 25 wherein for the purpose of illustration is shown a preferred embodiment of my invention and wherein:

Figure 1 is a perspective view of my attachment applied to a corn binder, the binder 30 being shown in dotted lines;

Figure 2 is a top plan view of the attachment, the supporting rod and the pivot pin being in section.

Referring now more particularly to the 35 drawings, the numerals 10 and 11 generally designate those portions of corn binder mechanism, known as the upper and lower trips. The function of these parts is to release the binder mechanism for operation and 40 they are operated by engagement of corn therewith. The binder mechanism includes a vertically extending brace 12 which is arranged at the right hand side of the machine and serves to hold the right hand top board 13 45 in its elevated position. Upon this brace, I pivotally secure an arm 14, so that it may swing in a horizontal plane. The arm 14 is preferably in the form of a flat strip, one end of which is rolled to produce an eye 15. This 50 eye has directed therethrough a pintle 16, which likewise extends through confronting flanges of angle plates 17. The other flanges 55 18 of the angle plates have openings for the

passage of arms of U-bolts 19, whereby they may be secured against the support 12. This 55 arm, when properly positioned, is arranged above and slightly in advance of the trip arms 10 and 11.

The binder mechanism further includes a brace 20 which is arranged in advance of the 60 brace 12 and at substantially the same level as the arm when in properly applied position. To this brace, I connect one end of a spring 21, the opposite end of which has engagement 65 with the arm 14 intermediate the ends thereof, such that it may be adjusted longitudinally of the arm to vary the tension applied thereto. The free end of the arm 14 projects in the path 70 of corn entering the binding mechanism and engages with the corn prior to its engagement with the trips 10 and 11, particularly when the corn is inclined at its upper end toward the binder. This arm serves to support a 75 large portion of the weight and to thereby permit a full load to enter the binder mechanism before the trip is actuated. By adjustment of the spring, the proper tension can be obtained to insure the proper load being received in the binder at all times.

Since the construction hereinbefore set 80 forth is capable of a certain range of change and modification without materially departing from the spirit of the invention, I do not limit myself to such specific structure except as hereinafter claimed.

I claim:

A supplemental trip attachment for a corn binder having a trip hook mounted for swinging movement upon a vertical axis, comprising a hinge support adapted to be applied to the frame of the binder at a point spaced from the axis of the trip hook, an arm pivoted at one end to the hinge member and arranged to swing in a plane transversely across the axis of the trip hook, a spring connected at one end 90 with the arm at a point between the pivoted end thereof and the axis of the trip hook, and being connected at its other end with the frame of the binder at a point in advance of the axis of the trip hook, said spring normally 95 holding the free end portion of the arm substantially in the vertical plane of the trip hook.

In testimony whereof I hereunto affix my signature.

HOWARD F. LYMAN.
